UNITED STATES PATENT OFFICE.

HENRY M. JUSTI, OF PHILADELPHIA, PENNSYLVANIA, ASSIGNOR TO
H. D. JUSTI & SON, OF PHILADELPHIA, PENNSYLVANIA, A FIRM.

MOUNT FOR DIATORIC TEETH.

SPECIFICATION forming part of Letters Patent No. 691,550, dated January 21, 1902.

Application filed May 7, 1901. Serial No. 59,086. (No model.)

To all whom it may concern:

Be it known that I, HENRY MARTIN JUSTI, a citizen of the United States, residing in the city and county of Philadelphia, State of Pennsylvania, have invented a new and useful Improvement in Mounts for Artificial Teeth, of which the following is a specification.

My invention consists of means applicable to an artificial tooth for affixing the same to a card or other mount for firmly supporting the tooth for the market, exhibition, and inspection in fine condition and with the best effects, the novel features of the same being pointed out in the claims.

15 Figure 1 represents a perspective view of a tooth embodying my invention. Fig. 2 represents a rear view thereof. Fig. 3 represents a vertical section thereof on line *x x*, Fig. 2. Fig. 4 represents a vertical section thereof on line *y y*, Fig. 3. Fig. 5 represents a vertical section of the tooth in primary condition. Fig. 6 represents a perspective view of the affixed device. Fig. 7 represents a plan view of teeth mounted in accordance 25 with my invention. Fig. 8 represents a vertical section on line *z z*, Fig. 7.

Similar letters of reference indicate corresponding parts in the figures.

Referring to the drawings, A represents an 30 artificial tooth known as a "diatoric" tooth, the same having therein the vertically-extending recess B and in the walls at the sides of said recess the cross-openings C, which latter are in communication with said recess.

35 D designates an attaching device, the same consisting of a loop, preferably of steel or other resilient material, having laterally-turned lips E, the legs F of said loop being at such distance apart that they may be fitted 40 into the recess B by proper manipulation of the same and portions of the same projecting outside of the tooth.

The operation is as follows: The legs are pressed together or contracted and introduced 45 in the recess B and the lips E are directed to the openings C, the loop then being let go, whereby said legs expand and said lips spring fully into said openings C, and the legs F engage with the adjacent side walls of the recess B,

50 it now being noticed that a portion of the body of the loop projects outside of the recess B, while it is firmly connected with the tooth. Teeth thus constituted may now be mounted by presenting them to a strip G of wax or

other pliable or flexible penetrable material 55 and the projecting portions of the loops stuck into said strip, whereby the loops are engaged with the same and the teeth firmly held on the strip as a mount, presenting the teeth in condition for the market, exhibition, inspection, &c., it being evident that a tooth may be readily removed from the strip and reapplied, all of which is accomplished in a simple, convenient, and inexpensive manner. When a tooth is removed, the legs of the loop 60 may be contracted, whereby the lips emerge from the cross-openings C, when the loop may now be displaced, leaving the tooth adapted for use when so desired. When the loop is displaced, any material from the strip G that 65 may clog the recess B and cross-openings C may be readily picked out and removed therefrom, the tooth being in normal condition, and the loop may be restored.

Having thus described my invention, what 75 I claim as new, and desire to secure by Letters Patent, is—

1. An artificial tooth having therein, a vertical recess, and cross-openings in the side wall thereof, in combination with a loop having expandible legs which partly occupy said recess and project partly outside of the same and are provided on their inner ends with lips which removably occupy said openings.

2. An artificial tooth having a recess and 85 cross-openings in the side walls thereof communicating therewith, a loop having expandible legs partly occupying said recess and projecting partly exterior thereof, lips on the inner ends of said legs adapted to occupy said 90 cross-openings, and a piece of pliable and penetrable material into which the exterior projecting portion of said loop is adapted to be stuck.

3. An artificial tooth having a recess, and 95 a cross-opening in the side wall communicating with said recess, a removable leg partly occupying said recess and partly projecting exterior thereof, a lip on said leg removably occupying said cross-opening, and a piece of 100 pliable and penetrable material into which the exterior portion of said leg is stuck and on which the body of the tooth rests.

HENRY M. JUSTI.
